UNITED STATES PATENT OFFICE.

FRANK L. PALMER, OF NEW LONDON, CONNECTICUT.

PATTERN MECHANISM FOR QUILTING-MACHINES.

SPECIFICATION forming part of Letters Patent No. 340,349, dated April 20, 1886.

Application filed December 23, 1885. Serial No. 186,890. (No model.)

To all whom it may concern:

Be it known that I, FRANK L. PALMER, of the city of New London, in the county of New London and State of Connecticut, have invented a new and useful Improvement in Pattern Mechanism for Quilting-Machines and other Purposes, of which the following is a specification.

My invention is more particularly intended for quilting-machines, but may be employed in other machines for controlling the relative change in position between two parts, one of which may be a tool or implement and the other of which may be the work or article operated on.

For quilting-machines my invention is applicable to machines comprising a sewing-machine and a fabric support or frame, whereon the fabric, or that portion thereof which is at any time being operated upon, may be held in a stretched or extended condition for the operation of the needle. In such machines one of the said parts—either the sewing-machine or the fabric support or frame—is movable in order to produce the change in relative position between the fabric and the needle necessary to produce sewing in any desired pattern on the fabric, and the movable part is guided or controlled by a pattern mechanism.

Although my invention may be embodied in pattern mechanism in which the elements are of different constructions and combined in different ways, its advantages are most apparent and will be most clearly understood if embodied in a pattern mechanism of the character shown and described in my United States Letters Patent No. 308,981, granted December 9, 1884, and in the Letters Patent No. 308,982, granted December 9, 1884, to Wm. H. Palmer, Jr., and I shall therefore describe the invention as embodied in a pattern mechanism of that character. The essential elements of such a pattern mechanism are a toothed or other rack or track arranged in pattern form and a pinion, wheel, or other engaging device gearing or engaging with the rack or track, and by its rotary motion or other positive operation effecting the necessary change in relative position between the rack or track and pinion or other engaging device.

When the pattern rack or track is connected with the movable fabric-support, as shown in my prior patent, No. 308,981, hereinabove referred to, the operation of the pinion on the 55 pattern rack or track will effect the automatic movement of the fabric under the sewing-machine needle along a line or lines corresponding to the form of the rack or track, and when the pinion is connected with a movable sewing-machine, as shown in the prior patent, No. 308,982, to Wm. H. Palmer, Jr., hereinabove referred to, the operation of the pinion on the rack or track will effect the movement of the sewing-machine needle over the fabric 65 in a line or lines corresponding to the form of the pattern rack or track.

Bed-comfortables and analogous large fabrics of rectangular form are much enhanced in appearance by quilting in patterns which 70 are appropriate to their shape, and the lines of which often cross each other; and a seemingly intricate pattern in which the lines of sewing are interlaced so as to form a beautiful design may be produced by repeating a 75 simple geometrical figure in different positions on the fabric. Such patterns would be difficult to produce in their entirety, because different portions of the rack or track would have to be in close proximity at parts of the pattern, and would have frequently to cross or intersect each other; and the object of my invention is to enable an entire design to be produced in quilting on the fabric by the use of a pattern mechanism comprising only a small 85 portion or portions of the design, such portion or portions being so arranged as to be capable of movement either manually or automatically, in order that they will in their different positions combine to produce the complete design 90 on the fabric.

In carrying out my invention I employ a pattern portion capable of movement into different operative positions, a shaft or device connected with the body to be moved, whether 95 it be the sewing-machine or the fabric-support, and engaging with the pattern portion, and a switch or shifting-gear arranged to be operated on by the shaft or device in order to move the pattern portion into different operative positions. I may also employ a movable pattern portion combined with another pat- 100

tern portion, which may also be movable and shifted by the operation of the shaft or device on a switch or shifting-gear, or which may be fixed in position. For example, I may employ a central circular pattern portion and an outer or surrounding pattern portion, one or each portion being turned relatively to the other portion by the action of the shaft or engaging device on a switch or switches, as fully hereinafter described.

In order to effect the turning or movement of the rotary pattern portion or portions, I may employ switches or shifting-gear consisting of a rack on the part to be turned and a wheel or sector engaging with the rack and carrying a lever or handle on which the shaft or engaging device acts to turn the movable portion. I also employ, in connection with the movable pattern portion or portions, locking devices which engage automatically with the movable portion and are operated on by the shaft or engaging device to automatically unlock the movable portion and permit it to be turned.

The invention consists in novel combinations of parts and features of construction, herein-after described, and pointed out in the claims.

In the accompanying drawings, Figure 1 is a plan of a pattern mechanism embodying my invention, and comprising inner and outer circular portions, each capable of turning relatively to the other. Figs. 2 and 3 are sectional views thereof, taken, respectively, on the planes indicated by the dotted lines $x-x$ and $y-y$, Fig. 1. Fig. 4 represents by dotted lines a design which may be produced by the aid of the pattern mechanism shown in Fig. 1; and Fig. 5 is a plan of a pattern mechanism also embodying my invention, and comprising an inner rotary portion and an outer or surrounding fixed portion.

Similar letters of reference designate corresponding parts in all the figures.

Referring first to Figs. 1, 2, and 3, A designates a central circular plate, and B an annular plate surrounding the same. As here represented, these two plates, which may be of wood or metal, are mounted upon a base-plate, C, so that they can turn relatively to and independently of each other. The central plate, A, is mounted upon a stud or pivot, a, and the outer plate, B, is held in place by the plate A and by an upturned rim, a', on the plate C. The plate A has in or upon it a groove, guide, or channel, b, which is here shown as formed by parallel flanges b b', one of which is plain and the other of which has upon its inner surface a toothed track or rack, b². The outer guide or channel, b*, is formed by flanges b*, upon one of which is a rack, b², these parts being similar to the groove or channel and rack shown as on the plate A, but different in form. The only purpose of the two plates A B is to support the grooves or guides and racks and the gearing hereinafter described, and hence these plates may be of skeleton

construction, and the rack and guide b² b may be considered as mounted upon the stud or pivot a, and the rack and guide b* b* as adjustable or movable circumferentially about 70 the rack and guide b² b.

D designates a shaft having upon its lower end a pinion, c, which enters the groove or guide portions b b* and engages or gears into the rack portions b² b²*. By its rotary motion and engagement with the rack portions the pinion c will travel along in a path corresponding to the shape of the rack portions, and will impart a corresponding movement to the part with which it is connected, whether it be 80 the fabric-support or the sewing-machine, as is described in the two patents hereinabove referred to. The two rack portions b² b²*, or the plates A B bearing them, are geared together by toothed racks d d*, secured, respectively, to the plates A B, and sectors e e*, pivoted, respectively, by pins or studs f to the plates B A. The sectors e e* are provided with arms or levers e' e'*², with which the shaft D may engage as the pinion c traverses the 90 rack portions b² b²*,

In order to prevent the accidental turning of the two plates A B and their rack portions, I provide locking devices whereby they may be locked to the base-plate C. As here represented, these locking devices consist of vertically-movable bolts g g*, which are respectively free to slide in the plates A B and engage with series of holes h h* in the plate C. These bolts are attached to levers g' g'*², which are fulcrumed at i, and are acted upon by springs i' to push the bolts downward into the holes, with which they engage.

I have here shown the shaft D as provided with a broad laterally-extending collar or flange, c', which, as the shaft D moves adjacent to one of the levers g' g'*², bears upon the top thereof, as shown in Fig. 2, and by depressing the tail end of the lever elevates its attached locking-bolt sufficiently to free it 110 from the base-plate C, as also shown in Fig. 2.

In the drawings, Fig. 1, the shaft D is supposed to be moving in the direction indicated by the arrow s, and has just passed out of engagement with the guide and rack portion b* b*² into engagement with the corresponding parts, b b². As the shaft enters the guide b its flange c' bears on the lever g'*², and by depressing it lifts the bolt g* out of engagement with the plate C, as seen in Fig. 2, and thereby unlocks the plate B. Before the flange c' releases the lever g'*² the shaft comes in contact with the lever or arm e*², and by acting thereon turns the sector e*², and through the engagement of the sector with the rack d* 115 turns the plate B forward in the direction indicated by the arrows s', Fig. 1, and thereby brings the guide and rack portion b* b*² into the position shown by dotted lines in Fig. 1, so that the shaft and pinion D c may pass readily 120 from engagement with the rack portion b² into engagement with the rack portion b*². The

lever and sector e^* e^* are turned into the position shown by dotted lines in Fig. 1, and as the locking-bolt g^* comes above the next hole h^* in the base-plate C it falls thereinto and locks the plate B in its new position. Before the shaft and pinion D leave the guide and rack portion b b^* , the flange c strikes upon the lever g' , and thereby unlocks the center plate, A , and as soon as the shaft D enters the guide b^* it comes in contact with the lever e' of the sector e , and by its action thereon and through the rack d turns the plate A one step ahead in the direction of the arrows s^2 , Fig. 1, in order to bring the end of the guide portion b at 15 which the shaft D enters it into coincidence with the end of the guide b^* at which the shaft D leaves it, in the new position which the guide portion b^* then occupies. By the turning of the plate A in the direction indicated by the arrows s^2 , the sector and lever e^* e^* will be returned from the position shown by dotted lines in Fig. 1 to the position shown by full lines, ready for the next operation of the shaft D upon it. In like manner, when the sector 20 and lever e^* e^* are operated to turn the plate B in the direction indicated by the arrows s' , the sector e and lever e' will be returned automatically from the position shown in full lines in Fig. 1 to their position, as indicated by dotted lines, ready for the next operation of 25 the shaft D thereon.

From the above description it will be seen that the two plates A B are thus moved step by step and alternately until they have completed their circuits, and thereby the needle of the sewing-machine will have been caused to produce on the fabric a design of the form shown in Fig. 4, and which is made entirely by repetitions of the figure in which the rack 30 and guide portions b^2 b^{2*} b b^* are laid out. It will also be understood that the whole design may be produced without once breaking the thread.

The example of my invention shown in Fig. 45 5 comprises an inner circular pattern portion, A , capable of rotation about the axis a , and a surrounding fixed pattern portion, B . The rotary portion A comprises a guide, b , formed by two flanges, b' b' , arranged in pattern form, 50 and on one of which is a toothed rack or track, b^2 . The pattern portion B comprises a number of duplicate guides, b^* , arranged around its circumference, and formed by flanges b^{2*} , on one of which is a toothed rack or track, b^{2*} . 55 When the central movable pattern portion is turned in the direction indicated by the arrows s^2 , the ends of the rack portion b^2 are successively brought into coincidence with the ends of the rack portions b^{2*} , so that the pinion and shaft D may readily pass from engagement with one into engagement with the other of them.

In each of the figures or parts of figures formed by the racks or tracks b^2 there is a 60 short vertical shaft or pin, f , carrying below the portion B a pinion, e , engaging with a

wheel or gear-teeth, d , formed around the edge of the central rotary portion, A , and on each shaft or pin f above the portion B is a ratchet-wheel, j . Loose on each shaft or pin f is a lever or handle, e' , carrying a pawl, j' , engaging the wheel j , and acted on by a spring, j'' , to swing it in the direction indicated by the arrows s^3 and against a stop, j^3 . I have also shown on the portion A a locking-lever, g' , the end of which engages successively with a circular series of notches, h , in the part B , and which are equal in number to the several different positions of the central rotary portion, A . The locking-lever g' is acted upon by a spring, i' , to force its tooth automatically into the notches h and hold the portion A against accidental turning. 75

As shown in the drawings, Fig. 5, the shaft D is in the pattern portion B , but is just about 80 entering the portion A . As it nears the end of the guide b in the part A the shaft D will strike the locking-lever g' and unlock the part A , and before the lever g' is released the shaft D will strike the adjacent lever e' , and, through 85 the pawl j' , ratchet-wheel j , and shaft f and pinion e , will turn the central portion, A , into its next operative position, and when it reaches such position the locking-lever will make engagement with the next notch, h , and 90 lock the portion A against accidental turning. 95

From the foregoing description it will be understood that the racks d d^* , the sectors and pinions e , and the levers e' constitute switches or shifting-gear for changing automatically the position of the movable pattern portion or portions. 100

What I claim as my invention, and desire to secure by Letters Patent, is—

1. In a pattern mechanism, the combination, with a pattern portion capable of movement into different operative positions, of a shaft or device engaging therewith and a switch or shifting-gear to be acted upon by the shaft or device to move the pattern portion into different operative positions, substantially as herein described. 105

2. In a pattern mechanism, the combination, with two pattern portions, one of which is movable into different operative positions relatively to the other, of a shaft or device engaging therewith and a switch or shifting-gear to be acted upon by the shaft or device to shift the movable pattern portion into different operative positions, substantially as 110 herein described. 115

3. In a pattern mechanism, the combination, with a pattern portion capable of movement into different operative positions, of a shaft or device engaging therewith, a switch or shifting-gear to be acted on by the shaft or device to move the pattern portion into different operative positions, and a locking device for securing the pattern portion against accidental movement, substantially as herein described. 125

4. In a pattern mechanism, the combination, with a pattern portion capable of movement

- into different operative positions, of a shaft or device engaging therewith, a switch or shifting-gear to be acted on by the shaft or device to move the pattern portion into different operative positions, and an automatic locking device for holding the pattern portion against accidental movement, and acted upon by the shaft or device to unlock the pattern portion, substantially as herein described.
10. 5. In a pattern mechanism, the combination, with a pattern portion capable of movement into different operative positions, of a shaft or device engaging therewith, and a switch or shifting-gear consisting of a rack and gear-sector, and a lever on which the shaft or device acts to shift the movable pattern portion into different operative positions, substantially as herein described.
15. 6. In a pattern mechanism, the combination of pattern portions, one of which is movable relatively to the other or others in order to make connection therewith when in the different positions to which it is moved, substantially as herein described.
20. 7. In a pattern mechanism, the combination of two pattern portions, each being movable relatively to the other in order to make connection with each other when in different positions, substantially as herein described.
25. 8. In a pattern mechanism, the combination, with two pattern portions, of a shaft or device for engaging therewith, one of said pattern portions being movable relatively to the other to bring their ends into coincidence when in different positions relatively to each other, so that the shaft or device may pass from one to the other of them while in different relative positions, substantially as herein described.
30. 9. In a pattern mechanism, the combination, with two pattern portions, of a shaft or device for engaging therewith, each pattern portion being movable relatively to the other to bring their ends into coincidence when in different positions, so that the shaft or device may pass from one to the other of them when in their different positions, substantially as herein described.
35. 10. In a pattern mechanism, the combination, with two pattern portions, of a shaft or device for engaging therewith, each pattern portion being movable relatively to the other to bring their ends into coincidence when in different operative positions, so that the shaft or device may pass from one to the other of them, and switches or shifting-gear to be acted upon by the shaft or device to shift the movable pattern portions into their different operative positions, substantially as herein described.
40. 11. In a pattern mechanism, the combination of two rotary pattern portions, to be turned each independently of the other, where by they may be made to register one with the other in different positions, substantially as herein described.
45. 12. In a pattern mechanism, the combination, with two rotary pattern portions, each comprising a groove or guide, and arranged to be turned each independently of the other, whereby the two grooves or guides will be made to coincide or register one with the other alternately at opposite ends thereof and in different positions around the center of the pattern, substantially as herein described.
50. 13. In a pattern mechanism, the combination of a central rotary portion, consisting of a track in pattern form, and an outer or surrounding rotary portion, also consisting of a track in pattern form, the two rotary portions being arranged to be turned independently of each other, whereby they may be made to register one with another in different positions around the center, substantially as herein described.
55. 14. In a pattern mechanism, the combination of a central rotary portion and an outer rotary portion arranged to turn independently of each other, whereby they may be made to register one with another in different positions around the center, a shaft or device engaging said pattern portions, and switches or shifting-gear connected with the pattern portions and arranged to be operated by the shaft or device while in engagement with one pattern portion to turn the other automatically to a new position, substantially as herein described.
60. 15. In a pattern mechanism, the combination of central and surrounding pattern portions, arranged to be turned each independently of the other, whereby they may be made to register one with another in different positions, a shaft or device engaging said pattern portions, switches or shifting-gear connected with the pattern portions and arranged to be operated by the shaft or device while in engagement with one pattern portion to turn the other automatically to a new position, and locking devices for holding the pattern portions against accidental turning, and arranged to be operated by the shaft or device to unlock the pattern portions at the desired times, substantially as herein described.
65. 16. In a pattern mechanism, the combination, with inner and outer rotary pattern portions, arranged to be turned one independently of the other, and a shaft or device engaging with said pattern portions, of locking-levers and attached locking-bolts upon which the shaft or device operates while in engagement with one pattern portion to unlock the other pattern portion and permit of its turning to a new position, substantially as herein described.
